CLAIM

The ornamental design for a spike for a loudspeaker, as shown and described.

DESCRIPTION

FIG. 1 is a side view of a spike for loudspeaker showing the new design including the bottom part and a top part placed adjacent to the bottom part; the front, back, right, and left side views being identical;

FIG. 2 is a top perspective view of a second configuration with the top part being vertically separate from the bottom part;

FIG. 3 is a top perspective view of the first configuration; FIG. 4 is a bottom view of the bottom of the spike in either one of the first or second configurations;

FIG. 5 is a bottom view of the top part of the spike in the second configuration;

FIG. 6 is a side view of the spike for a loudspeaker in the second configuration showing the new design, the front, back, right and left side views being identical;

FIG. 7 is a top view of either one of the first or second configurations;

FIG. 8 is a bottom perspective view of the second configuration; and,

FIG. 9 is a bottom perspective view of the first configuration. The broken lines are directed to environment and form no part of the claimed design.
